DESIGN FOR A PAN GREASING MACHINE

Harold A. Roselund, Toledo, Ohio, assignor to The
De Vilbiss Company, Toledo, Ohio, a corpora-
tion of Ohio

Application June 11, 1940, Serial No. 92,926

Term of patent 7 years

To all whom it may concern:

Be it known that I, Harold A. Roselund, a citizen of the United States and resident of Toledo, in the county of Lucas and State of Ohio, have invented a new, original, and ornamental Design for a Pan Greasing Machine, of which the following is a specification, reference being had to the accompanying drawing, forming a part thereof.

In the drawing, Figure 1 is a side perspective view of a pan greasing machine showing my new

design and Figure 2 is a perspective view of the left hand end of the machine shown in Figure 1. The other side of the right hand end of the apparatus as presented in Figure 1, is identical in appearance to the side of the end shown in this view.

I claim:

The ornamental design for a pan greasing machine, as shown and described.

HAROLD A. ROSELUND.
